WHEEL COVER

Frederic P. Plotkin, Los Angeles, Calif.

Application February 2, 1959, Serial No. 54,403

Term of patent 14 years

(Cl. D14—30)

Fig. 1 is a front view of a wheel cover, showing my new design;

Fig. 2 is a cross-section taken along the line of 2—2 of Fig. 1, and

Fig. 3 is a perspective view of the wheel cover shown in Fig. 1.

I claim:

The ornamental design for a wheel cover, substantially as shown.
